UNITED STATES PATENT OFFICE.

WILLIAM A. BRUBAKER, OF AKRON, OHIO, ASSIGNOR TO THE MILLER RUBBER COMPANY, OF AKRON, OHIO, A CORPORATION OF OHIO.

MACHINE FOR STRIPPING HOLLOW ARTICLES FROM THEIR FORMS.

1,220,177.

Specification of Letters Patent.

Patented Mar. 27, 1917.

Application filed October 30, 1916. Serial No. 128,543.

To all whom it may concern:

Be it known that I, WILLIAM A. BRUBAKER, a citizen of the United States, and resident of Akron, Ohio, have invented certain new and useful Improvements in Machines for Stripping Hollow Articles from their Forms, of which the following is a specification.

This invention relates to apparatus for the stripping or removal of flexible articles from the forms on which they are formed or treated, such, for instance, as toy balloons and similar articles which are constructed by the dipping of glycerin coated forms in a suitable rubber solution which are thereafter vulcanized. Considerable difficulty has been heretofore experienced in removing these articles, which is not only due to the character of the article itself but also to the fact that the form is coated with glycerin or other similar material to prevent the balloon from sticking to the form. When the stripping operation is commenced and the article begins to turn inside out, the inner glycerin coated surface is presented for contact which, due to its extreme slippery nature, greatly impedes the stripping action.

Among the objects of the present invention are to provide a machine or apparatus which will support the forms and expeditiously effect the stripping of the balloons therefrom. I have also aimed to provide means for overcoming the difficulty caused by the glycerin or other coating.

With these and various other objects in view, not necessary to enumerate, in view of the following specification, the invention includes the novel features of construction and arrangement of parts hereinafter described and illustrated in the accompanying drawings, the invention being defined by the claims appended hereto.

An embodiment of my invention is illustrated in the accompanying drawings, in which—

Figure 1 is a plan view of the machine,

Fig. 2 is a side elevation of the same,

Fig. 3 is a view at right angles to Fig. 2,

Figs. 4 and 5 are detail views on a larger scale.

Referring by reference characters to these drawings, the numeral 1 designates a base plate, upon which the other parts of the machine are supported. Located upon the

base plate 1 is a pedestal 2, which in turn supports a vertical shaft 3, upon which is rotatably mounted a circular table or carrier 4, carrying a bevel gear 5. The pedestal 2 also supports a horizontal bearing 6, through which a shaft 7 extends. The shaft 7 is provided at one extremity with a beveled gear 8 meshing with the bevel gear 5, and rotation of shaft 7 is imparted through bevel gears 8 and 5 to the table 4. Table 4 is provided with a plurality of concentric vertical flanges 4^a and 4^b. Equally spaced around table 4 are spring pressed plungers 9 extending radially from the center of said table and having squared portions 9^a at their outer extremities and vertical pins 9^b at their inner extremities. The annular flange 4^a supports a circular plate 10 having radial slots 10^a correspondingly spaced with the spring plungers 9, in which pins 9^b enter and hold the plungers against turning and also limit the radial movement thereof. The squared portions 9^a of the spring plungers 9 are provided with vertical pins 9^c of dimensions suitable to correspond with the holes in the forms used. Portions 9^a are also provided with studs 9^d screwthreaded to their lower sides and surrounded by anti-friction rollers 11. The annular flange 4^b of the circular plate 10 is provided with an outwardly extending rim 4^e at its upper edge, said rim being provided with semi-circular notches (see Fig. 1), whose positions correspond with the positions of pins 9^c. These notches are formed in such a way that when spring bolts 9 are forced to their inward limits, the pins 9^c will be concentric with said semi-circular notches, and the walls of said notches will prevent upward displacement of the wooden forms located upon pins 9^c, by engaging enlarged bases 9^f or flanges on the forms which cannot pass through the notches (see Fig. 2). Also supported from base plate 1 are vertical columns 12, which support at their upper extremities a cam plate 13 in juxtaposition to the rollers 10^a 11. This cam plate 13 is of such form that during a certain interval of the rotation of table 4, each spring bolt 9 will be forced to its inward limit, thus locking the forms beneath the out-turned flange of table 4, and during the remainder of the revolution of table 4 spring bolts 9 will be allowed to return to their outward or normal position,

so that the forms may be easily placed thereon and removed therefrom.

Referring now to shaft 7, which passes through bearing 6 and carries the beveled gear 8 at its one extremity, as before stated, this shaft carries at its other extremity a ratchet wheel 14 keyed thereon. Shaft 7 also carries, in juxtaposition to the ratchet wheel 14, a bell crank lever 15 rotatably mounted thereon and carrying at the end of its shorter arm a pawl 16 impinging on said ratchet wheel 14. The longer arm of bell crank lever 15 is provided with a roller 17 and also with a spiral tension spring 18, whose opposite end is connected to base plate 1. Roller 17 bears upon a cam 19 fast on one extremity of a horizontal shaft 20, said horizontal shaft being continuously driven at a suitable speed. It will thus be seen that by the means described, table 4 will be given a step by step, or intermittent, motion, the shape of cam 19 and dimensions of levers 15 and beveled gears 8 and 5 being such that the angular motion imparted to table 4 by one revolution of shaft 20 will correspond with the distance between any two adjacent pins 9^c upon table 4. Shaft 20 derives its power through worm gear 21 meshing with worm 22 fastened on a horizontal shaft 23 which carries gear wheel 24 at its other extremity, which in turn meshes with gear 25 on power shaft 26, which latter may be provided with a pulley 27, or other driving means.

Base plate 1 is provided with a bracket 28 having two bosses 28^a at its upper extremity, said bosses 28^a supporting rigid vertical guide rods or bars 29, which are connected together at their upper extremities by a tie bar 30 insuring the equal spacing of the same. A carriage 31 is arranged to reciprocate vertically on these guide bars and is operated by a roller 32 impinging on a cam 33. Cam 33 is keyed upon a shaft 34, which also carries a gear 35, which in turn is driven through an intermediate gear 36 from a driving gear 37 mounted upon a shaft 38. Shaft 38 carries at its opposite extremity a beveled gear 39 meshing with a beveled gear 40 located upon shaft 20. Through the aforesaid gearing, cam 33 and cam roller 32, carriage 31 is caused to slide vertically upon guide bars 29. Carriage 31 has suitable bearings which support a vertical shaft 41 and the lower end of said shaft is provided with a spline or key-way and projects through a quill beveled gear 42, which also meshes with beveled gear 40 upon shaft 20, deriving motion therefrom. Through this mechanism shaft 41 is rotated continuously, regardless of the vertical location of carriage 31. Shaft 41 is provided at its upper extremity with a beveled gear 43 fixed thereon. Carriage 31 is provided with horizontal bearings 31^a (see Fig. 4)

carrying a shaft 44. Shaft 44 is provided with a beveled gear 45 meshing with beveled gear 43. Shaft 44 also carries a spur gear 46 and a beveled gear 47. Carriage 31 also supports the horizontal shaft 48 placed at right angles to shaft 44 and carrying a beveled gear 49 which meshes with aforesaid beveled gear 47. Shaft 48 also supports a spur gear 50. Carriage 31 supports horizontal shafts 51^a and 51^b parallel to shaft 48 and equally spaced therefrom, which shafts 51^a and 51^b carry at one end spur gears 52^a and 52^b, meshing with spur gear 50 on shaft 48, and on their opposite ends beveled gears 54^a and 54^b. Shafts 51^a and 51^b also support arms 53^a and 53^b which are pivoted thereon. Arms 53^a and 53^b are provided with bearings in which are mounted longitudinal shafts 55^a and 55^b, which are provided with beveled gears 56^a and 56^b, meshing with gears 54^a and 54^b, but oppositely located so as to cause opposite directions of rotation in shafts 55^a and 55^b. Shafts 55^a and 55^b are provided at their lower extremities with beveled gears 57^a and 57^b fast thereon. Said arms 53^a and 53^b are provided at their lower extremities with horizontal bearings in which are located shafts 58^a and 58^b carrying beveled gears 59^a and 59^b meshing respectively with bevel gears 57^a and 57^b. Fast on shafts 58^a and 58^b are concave-faced composition rollers 60^a and 60^b located in such a position that the line of travel of pins 9^c passes equidistantly between said rollers, as shown in Fig. 5. Rollers 60^a and 60^b may be made of any suitable frictional material, but I prefer to make them of a soft rubber composition. Carriage 31 supports a horizontal shaft 61, which is placed above shaft 48 and at an angle of 90° thereto. Said shaft 61 carries a spur gear 62 (Fig. 2), which meshes with spur gear 46 carried by shaft 44. Shaft 61 also carries opposed face cams 63^a and 63^b fastened thereto (see Fig. 5). Arms 53^a and 53^b are provided with cam rollers 64^a and 64^b which impinge against cams 63^a and 63^b, and said arms are also provided with crossed horizontal extensions 65^a and 65^b which are provided with eye bolts 66^a and 66^b at their outer extremities. A tension coil spring 67 connected between said eye bolts 66^a and 66^b serves to keep cam rollers 64^a and 64^b in contact with the faces of cams 63^a and 63^b, and the action of cams 63^a and 63^b is such as to cause arms 53^a and 53^b to oscillate upon shafts 51^a and 51^b, thereby causing alternate separation and approach of the composition rolls 60^a and 60^b independent of the continuous rotation of said rolls.

At a certain interval in the operation of this machine the table 4 will be ratcheted to such a position that one of the pins 9^c carrying a form, will pass to a position equi-

distant between the rollers 60^a and 60^b, and at this point the table 4 will rest. The cam 33 is synchronized with the cam 19 which rotates the table 4 and said cam 33 is of such shape that carriage 31 will have reached its lowest position at the same instant that table 4 comes to rest. Cams 63^a and 63^b are also synchronized with cams 33 and 19 and will be of such shape that at the aforesaid instant the composition rollers 60^a and 60^b will be at their farthest distance apart. The shape of cams 63^a and 63^b is such that during the period when the table 4 is at rest, the composition rolls 60^a and 60^b travel toward each other until they come in contact with the lowest position upon the form. During this time cam 33 is laid out with a dwell so that carriage 31 is also resting during this period. During the next interval cam 33 forces the carriage 31 upwardly and cams 63^a and 63^b are laid out to such shapes that the composition rollers 60^a, 60^b may follow the shape of said form approximately, any irregularities in said form being taken care of by the fact that rollers 60^a, 60^b are spring pressed by spring 67 toward the form and are held to approximately the shape of the form of cams 63^a, 63^b. It will be noted that during these operations composition rollers 60^a, 60^b are operating in continuous opposite rotation, said rotation being of such a direction as to roll the rubber article toward the upper extremity of the form, and as carriage 31 rises, rolls 60^a, 60^b will continue to keep in contact with the rolled up portion of said balloon. After rolls 60^a, 60^b have passed the largest diameter of said form, rolls 60^a, 60^b will continue to separate rather than follow the shape of the form and will be far enough apart so that as the table 4 starts to rotate the second time, there will be ample space between the arms 53^a, 53^b for the said form to pass between said arms to its next position and for the next form, upon table 4, to take the position assumed by the form first mentioned. The carriage 31 now descends rapidly, at the same time the arms 53^a, 53^b being held apart until the first position described is assumed. I also provide the machine with a containing tank 68 having a sifter mechanism 69, simulating a flour sieve, which may be continuously driven from any convenient part of the machine, such as a sprocket 70 located upon shaft 61 and provided with a chain 71. I also provide the machine with a chute 72 extending from said sifter 69 to a position vertically above the position assumed by the form operated upon. The purpose of said container 68 is to hold a supply of talc or soap stone powder, which I find necessary to the successful operation of the machine, due to the fact that the composition rollers 60 accumulate 65 a coating of glycerin, with which the

wooden forms are coated beneath the rubber to prevent adhesion of the same, and consequently the rollers will be caused to slip upon the balloon and lose their hold if not provided with an ample supply of soap stone or similar dust which absorbs said glycerin.

What I claim is:—

1. In an apparatus of the class described, a moving carrier for supporting a form bearing an article to be stripped therefrom, rotatable stripping rolls mounted for movement toward and from each other to yieldingly bear against said form, and means for bodily moving said stripping rolls perpendicularly of the form.

2. In an apparatus of the class described, a moving carrier for supporting a form bearing an article to be stripped therefrom, rotatable stripping rolls mounted for movement toward and from each other to yieldingly bear against said form, means for bodily moving said stripping rolls perpendicularly of the form, and means for feeding friction producing material to prevent slipping of the rolls on the article.

3. In an apparatus of the class described, an intermittently moving carrier for supporting forms bearing articles to be stripped therefrom, rotatable stripping rolls mounted for movement toward and from each other to embrace and contact with the forms, and means for imparting bodily movement to said rolls lengthwise of the forms while the carrier is at rest.

4. In an apparatus of the class described, an intermittently moving carrier for supporting forms bearing articles to be stripped therefrom, rotatable stripping rolls mounted for movement toward and from each other to embrace and contact with the forms, means for imparting bodily movement to said rolls lengthwise of the forms while the carrier is at rest, and means for feeding friction producing material between the rolls and articles on the forms.

5. In an apparatus of the class described, a pair of rotating stripping rolls movable toward and from each other while spaced apart, means for imparting bodily movement to said rolls in a plane perpendicular to the plane of their movement toward and from each other, and means for presenting a form bearing an article to be stripped therefrom between said rolls and holding it during the bodily movement of the rolls.

6. In an apparatus of the class described, an intermittently moving carrier for supporting forms for bearing articles to be stripped therefrom, a pair of rotating stripping rolls movable toward and from each other while spaced apart and movable bodily in a plane perpendicular to the plane of movement of the carrier, and means for imparting such bodily movement to the rolls.

while embracing the form when the carrier is at rest.

7. In an apparatus of the class described, an intermittently moving carrier, for supporting forms bearing articles to be stripped therefrom, a pair of rotating stripping rolls movable toward and from each other while spaced apart and movable bodily in a plane perpendicular to the plane of movement of the carrier, means for imparting such bodily movement to the rolls while embracing the form when the carrier is at rest, and means for feeding friction producing material during the stripping action.
15. 8. In an apparatus of the class described, a support for a form bearing an article to be stripped therefrom, a plurality of stripping members, movable toward and from each other while spaced apart, means for 20 yieldingly pressing said members toward each other, means for positively moving said members away from each other against the yielding action, and automatic means for causing a separation of said support and 25 stripping members while said members are in stripping relation to the form.

9. In an apparatus of the class described, an intermittently moving support, for a form bearing an article to be stripped therefrom, and a pair of stripping members for embracing said form and operable while the support is stationary to strip said article from the form.

10. In an apparatus of the class described, 35 an endless moving carrier, means for removably holding on said carrier forms for carrying articles to be stripped therefrom, a plurality of rotatable friction members mounted for movement toward a common 40 center while out of contact with each other, means for causing a relative separation of the friction members and carried in a plane perpendicular to the carrier while said friction members are in engagement, and means 45 for rotating said friction members.

11. In combination, a rotary table having a step by step movement, adapted to carry forms bearing articles to be stripped therefrom, a plurality of stripping members located at a fixed point in the travel of the table, and means for separating said members to permit entrance of a form therebetween, causing them to frictionally engage the form and move bodily away from the 55 table while in such engagement during the time the table is stationary and finally return toward the table in open position to receive a fresh form.

12. In combination, a support for detachably holding a form carrying an article to be stripped therefrom, a plurality of opposed rotating stripping rolls, cam controlled means for holding them spaced apart and varying the distance therebetween while 65 so spaced, tension means tending to yield-

ingly press said rolls toward each other, and means for moving said rolls bodily away from the form support.

13. In combination, a support for detachably holding a form bearing an article to be stripped therefrom, a plurality of opposed rotating stripping rolls, spring means for pressing said rolls toward each other, cam controlled means for intermittently forcing said rolls apart against the action of the 75 springs, and automatic means for causing said rolls and said support to have relative bodily movement toward and from each other.

14. In combination, a support for detachably holding a form carrying an article to be stripped therefrom, a carriage movable toward and from the support, a pair of levers supported from said carriage, a pair of stripping members supported from said levers, spring means acting on said levers tending to press said stripping members into contact with the form, cam means co-acting with said levers to force the rolls apart against the spring tension and means for 90 reciprocating said carriage.

15. In combination, a support for detachably carrying a form bearing an article to be stripped therefrom, a pair of levers carrying co-acting rotating stripping rolls, 95 spring means acting on said levers tending to rock them to hold the rolls in contact with the form, cam means acting on said levers to force them apart against the tension of the spring means, and supporting means for 100 said levers operable to move the same toward and from the support.

16. In combination an intermittently moving endless carrier, means for detachably connecting thereto forms for carrying 105 articles to be stripped therefrom, a pair of rotating stripping rolls located at a fixed point in the travel of said carrier and movable toward and from each other while out of contact with one another, and means for 110 moving said rolls bodily in a plane perpendicular to the table in unison with the intermittent movement thereof.

17. In combination, an endless moving carrier, spindles carried thereby, adapted to 115 carry forms for supporting articles to be stripped therefrom, said forms having base flanges, means carried by the carrier for engaging said base flanges to hold the forms to the carrier, upwardly rotating spaced 120 rollers located at a fixed point in the travel of the carrier for stripping articles from the forms, and means for moving the rolls bodily away from the carrier during the stripping action.

18. In combination, a rotating table, a plurality of radially arranged reciprocating plungers, means for alternately extending and retracting said plungers, spindles carried by the outer ends of said plungers, 130

- adapted to support forms for carrying articles to be stripped therefrom, which forms have base flanges, means carried by the table for engaging said base flanges when the 5 plungers are retracted to hold the forms on the table and upwardly acting stripping means co-acting with the forms while so held.
19. In combination, a rotating table having a pair of vertical flanges, a plurality of radially arranged reciprocating plungers non-rotatably guided in said flanges, springs tending to force said plungers normally outward, vertical spindles carried by the outer 10 ends of said plungers for carrying forms having projecting base flanges, said table having an annular flange provided with recesses to receive the spindles and have their walls overhang the flanges when the plungers are retracted, cam means for retracting the plungers, and stripping means located at a fixed point in the travel of the table.
20. In combination, an intermittently moving horizontal carrier with means for 15 operating it, a carriage mounted to reciprocate vertically in unison with the movements of the carrier, a pair of levers pivotally supported from said carrier, said carrier being adapted to detachably carry forms bearing 20 articles to be stripped therefrom, a pair of rotary stripping rolls carried by the lower ends of said levers in position to contact with opposing sides of said forms, spring means acting on said levers tending to hold 25 the rolls in contact with the form, cam means for operating on said levers to force the rolls apart, and driving means operating through said levers for rotating said rolls.
21. In an apparatus of the class described 30 a support for holding an article to be operated upon in a fixed position, a pair of swinging arms carrying rotary friction elements adapted to impinge on opposite sides of said article, means operating on said arms 35 tending to yieldingly press the elements into contact with the opposite sides of the article, and cam means for co-operating with said arms for forcing the elements away from each other, and means for rotating the elements. 50
22. In an apparatus of the class described, a support for holding an article to be operated upon in a fixed position, a pair of swinging arms carrying rotary friction elements adapted to impinge on opposite sides of said article, means operating on said arms tending to yieldingly press the elements into contact with the opposite sides of the article and cam means for co-operating with said arms for forcing the elements away from each other, means for bodily moving said arms relative to the article, and means for rotating said elements. 55
23. In combination a support for an article to be operated upon of irregular 60 form, a carriage movable with relation to said support, a pair of levers pivotally supported from said carriage, a pair of rotary friction elements carried by the lower ends of said levers, means for reciprocating the 65 carriage, and means for moving the friction elements toward and from each other. 70
24. In an apparatus of the class described, an intermittently moving carrier for supporting forms bearing articles to be stripped 75 therefrom, stripping elements mounted for movement toward and from each other to embrace and contact with the forms, and means for imparting bodily movement to said stripping elements lengthwise of the 80 forms while the carrier is at rest. 85
25. In an apparatus of the class described, a support for a form bearing an article to be stripped therefrom, a plurality of stripping members movable toward and from 85 each other while spaced apart, means for causing a separation of said support and stripping members while the parts are in stripping relation, and means for feeding friction producing material during the stripping action. 90

In testimony whereof, I affix my signature.

WILLIAM A. BRUBAKER.
